UNITED STATES PATENT OFFICE.

FREDERICK MANKEY, OF WILLIAMSPORT, PENNSYLVANIA.

DESIGN FOR A PANEL.

SPECIFICATION forming part of Design No. 16,234, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photographs, forming part hereof.

Figure 1 is a plan view of my design. Fig. 2 is a section transversely of a surface provided with elevations B C D E, and is here presented to show the contour of said elevations.

My design relates to an ornamental panel for doors, wainscots, &c.; and it consists in a raised frusto-pyramidal rectangular elevation, A, disposed centrally in said panel. B, C, D, and E are series of elongated elevations, each series occupying about one-quarter of the panel and placed diagonally thereon in directions parallel to the sides of the central eleva-

tion, A. The upper sides of the elevations B C D E are formed by inclined planes meeting on the central longitudinal line, as indicated in Fig. 2. Between the elevations B C D E are spaces or channels F.

25

I claim—

The design for a panel, substantially as herein shown and described, which consists in a rectangular frusto-pyramidal elevation, A, in the center of the panel, and diagonal elevations B C D E, disposed, respectively, parallel to the several sides of the elevation A, the said elevations B C D E having upper surfaces formed by two inclined planes, and intermediate channels or spaces, F, between said elevations B C D E.

30 FREDERICK MANKEY.
